UNITED STATES PATENT OFFICE.

GEORGE DAVID WATSON, OF LITHGOW, NEW SOUTH WALES, AUSTRALIA, ASSIGNOR
TO CORKSCREW STEEL FENCES LTD., OF SYDNEY, NEW SOUTH WALES, AUSTRALIA,
A COMPANY OF NEW SOUTH WALES, AUSTRALIA.

FENCE STANDARD.

Application filed May 10, 1926, Serial No. 103,113, and in Australia September 21, 1925.

This invention relates to fence standards, of the type which consists of a metal bar helically twisted throughout its entire length and of a cross section such that the two edges 5 are made thicker than the central portion on both faces of the bar.

A helically twisted metal fence standard has already been proposed, the bottom end 10 of which is pointed so that it may be bored into the ground without the aid of great pressure.

According to the present invention the fencing standard consists in a metal bar having a relatively thin web and heavy and integral marginal reinforcing flanges, helically 15 twisted throughout its entire length flattened at one end and sharpened at the other and provided where necessary with means for the reception of fencing wire.

20 In the accompanying drawings which illustrate a standard constructed according to this invention:—

Figure 1, is a perspective view of the standard,

25 Figure 2, is a cross section of same, and

Figure 3, is a fragmentary perspective view of a slightly modified form of means for fastening fencing rods to the standard.

The standards 4 in the drawings are 30 formed of metal bars having H or I cross section as illustrated in Figure 2. The bars are twisted into the form shown and the lower end is pointed as at 5 to enable it to enter the ground easily while a short flat section 35 as at 6 is left at the top. Holes 7 are provided where necessary for the reception of the wires and a slot 8 is formed in the top of the standard.

The fence wires may, if desired, be at-

tached as shown at 12 in Figure 3 the wire 40 being lashed to the standard 4' the adjacent turns of which maintain it in position.

Although the section of the standard has been referred to and described as H or I it may be of any section having a relatively 45 thin web and heavy reinforcing marginal flanges.

The number of turns per foot may also be varied as well the number and the arrangement of wire holes or lashings. 50

It should be appreciated that the reinforcing marginal flanges consist in not only increasing the durability of the standard but facilitate the mounting of the standard in the bearing by increasing the rigidity of the 55 standard without in any manner interfering with the embedding of the standard. Moreover the adjacent turns of the standard at the points 12 where the wire is lashed form substantial recesses and the thickened marginal portion presents a smooth incutting surface which reduces the possibility of the 60 breakage of the wire as well as the lashes.

I claim:

A fencing standard consisting of a metal 65 bar having a relatively thin web and heavy integral reinforcing flanges along opposite marginal edges, and helically twisted throughout its entire length and flattened at one end and sharpened at the other, the upper end of the web being provided with a 70 wire receiving slot, and the bar being provided with means throughout the length thereof for the reception of fencing wires.

In testimony whereof I have affixed by 75 signature.

GEORGE DAVID WATSON.
